UNITED STATES PATENT OFFICE.

JOHN H. FORREST, OF MARION, INDIANA.

TYPE-WRITING MACHINE.

SPECIFICATION forming part of Letters Patent No. 438,617, dated October 21, 1890.

Application filed November 1, 1886. Serial No. 217,746. (Model.)

To all whom it may concern:

Be it known that I, JOHN H. FORREST, a citizen of the United States, residing at Marion, in the county of Grant and State of Indiana, have invented a new and useful Type-Writing Machine, of which the following is a specification.

My invention relates to improvements in type-writing machines in which movable keys by mechanical connection with a wheel with flexible arms carrying fixed types, of metal, rubber, or other material, operate in conjunction with said wheel and arms to print the letters of the alphabet and numerals into words on paper or other substance; and the objects of my improvements are, first, to increase speed and accuracy in type-writing; second, to facilitate and cheapen type-writing in various styles of type; third, to simplify and increase the capacity of type-writing machines and reduce their cost and size, and, fourth, to increase the durability of type-writing machines. I attain these objects by the mechanism illustrated in the accompanying drawings, in which—

Figure 1 is a vertical section of the machine, illustrating the adjustment and method of operating the letter-keys, the key-board, and levers and their connections, and of the carriage and its connections. Fig. 2 is a vertical section of part of the machine, showing the letter-wheel and letter-hammer and their connections and mode of operation. Fig. 3 is a vertical section of part of the machine, showing the ratchet or stop, its connections, and mode of operation. Fig. 4 is a top view of the letter-wheel, beneath the arms of which the letters are fixed. Fig. 5 is a detailed view of the ratchet and ratchet-wheel used to operate the carriage. Fig. 6 is a detailed view of the letter-key.

Similar letters refer to similar parts throughout the several views.

The wheel A has flat flexible projecting arms B, to which are secured at or near their ends types, of metal, rubber, or other suitable material, all operated by the mechanical devices following: a hammer-lever C, so formed that one end can be operated as a hammer upon the letter-bearing arms of the wheel above described and strike on the letter-arms on the side opposite the respective types, and

thus drive them upon the paper or other material placed to receive the impress of the types.

The lever and hammer described are operated as follows: The hammer-lever is supported by a bridge or beam, as at D, and at the end of the hammer-lever is attached a link E, connecting with a lever F upon a support G, and said lever F is connected with a link H, which is connected with a key-board K, the fastenings and connections of said levers, links, and supports being by flexible joints. The letter-key L, or any other letter-key, when pressed down will rotate the wheel so as to bring the corresponding letter directly under the hammer, and the continued pressure on the key and key-board will drive the link H downward, and, operating on its connections, cause the hammer to strike upon the type-arm, thus imprinting the letter on the paper or other material beneath it.

Beneath the hammer-lever is a second bridge or beam o over the letter-wheel A, and in this bridge or beam is a set-screw to regulate the blow of the hammer upon the types and prevent injury to the types by too hard a blow or too long a sweep of the hammer-arm.

The letter-key rests on the lever m, furnished with a cogged arc n, made to match the wheel and cogged arm O. The spring P, or other proper springs, supports the levers m at an elevation or depression, as the case may be, sufficient to disconnect the same from the wheel O when the letter-key is not in use.

The elevation and depression of the cogged arcs n are arrested at the points of disconnection from the wheels and cogged arms O by means of the transverse bars r and s, supported on the posts R and S, placed at each side of the machine, or by other secure supports.

When the pressure is applied to the key L, the arc n is brought into connection with the wheel O, which is fixed on the shaft a, causing the wheel and shaft to revolve, and thus rotate wheel A by acting on the connecting cogged wheels W and X. The pressure of the key upon the lever m lowers the lever and presses down the transverse bar v and lifts the ratchet T out of the slot in the wheel w, which is fixed upon the transverse shaft a, and at the moment the ratchet is withdrawn

- from the slot the cogged arc n connects with the cogged wheel O and rotates the same, operating through the wheels W and X , turning the letter-wheel A , as above described.
- 5 When the lever m is returned to the point of disconnection from the wheel O by the pressure of springs, as above stated, the ratchet T , moving on the pivot i , drops back into the slot of the wheel w by force of the spring K or 10 other suitable spring and holds the cogged wheel O in exact position to receive at the proper point the stroke of the ascending or descending cogs of the levers m when operated by downward pressure on the letter- 15 keys. The key-board K , operating on a fulcrum at e , is, by the operation of proper springs after removal of the pressure from it, returned to its proper place. The levers m also are returned to their point of disconnection from the wheels O by the use of proper 20 springs for that purpose. These levers m are of two classes, the cogs of one class ascending and of the other class descending by pressure on the letter-keys. The fulcrum of one 25 class of levers is upon a transverse shaft at g and the other upon a transverse shaft at g . The levers m are held firmly in position and move in the slot in the post h . These levers disconnect from the cogged wheels O only 30 when the pressure is removed from the keys. To prevent such disconnection during the pressure of the letter-keys and to prevent the letter-wheel A from being turned too far by such pressure, a stop is provided, consisting 35 of the transverse bar z , supported by posts or other firm support. In the transverse bar z are placed set-screws—one for each lever—to regulate the descent of the levers and fix the exact distance the wheel may turn in 40 order to bring the required letter to its proper place to receive the stroke of the hammer.
- By means of the two classes of levers, with different movements, as above described, an advantage accrues from the fact that the letter-wheel need not be rotated more than half 45 a revolution to bring any letter upon it to the proper place to receive the stroke of the hammer, and the highest attainable speed in printing is thus secured.
- 50 The number of letters, figures, signs, and characters which may be printed with this machine can be increased to any desired number by making the letter-wheel larger and the machine wide enough to receive the increased 55 number of levers m and cogged wheels O required to print the additional letters, figures, signs, and characters. In this way the machine may be made of any desired capacity without materially impairing its speed or ease 60 of operation.
- The paper or other material on which the type-writing is done is fed into the machine by forcing it through the crevice u by means of a revolving roller d in the carriage Q . This 65 carriage Q is moved by the cogged wheel y , operating in the cogs along the edge of the carriage. The cogged wheel y is fixed upon

the end of a shaft J , having at the other end the ratchet-wheel x , operated by the ratchet I . The pressure on the key-board, causing 70 the hammer-lever to strike the letter-arm, also causes the ratchet to recede upon the ratchet-wheel, and the force of the rising-key-board, when the pressure is removed, causes the ratchet to turn the ratchet-wheel and the 75 wheel y , and thus moves the carriage to the point required.

When the printing of a line is completed, the carriage is returned by hand and adjusted for another line by means of a set-screw or 80 fixed wheel at the end of the roller d . By pulling the knob f , connected with the ratchet I by the wire or rod p , the ratchet is disconnected from the ratchet-wheel x , and the carriage may be easily returned in the manner 85 stated, and when the knob is released the ratchet resumes its place by force of the spiral spring or other suitable springs, as at c .

The letter-wheel A is held firmly between clamps upon its opposite sides, the upper one 90 of which is shown at j , and the letter-wheel between these clamps is screwed down firm and solid on the end of the shaft t . The letter-wheel can easily be removed and replaced by other similar wheels bearing the same or 95 different styles of type, enabling the operator of the machine to write or print in a variety of styles with very little additional expense or trouble.

In writing in different styles it may become 100 necessary to increase the space between the letters, which is done by shifting the ratchet I from right to left or from left to right along the slot b in the shaft F , so as to increase or diminish the number of cogs passed over by 105 the point of the ratchet when lowered by pressure on the key-board K , the distance the carriage Q is moved depending upon the number of small cogs on the ratchet-wheel x taken up by the point of the ratchet at each 110 pressure of the key-board.

The rim of the ratchet-wheel x is made wide enough to permit the ratchet to be shifted from side to side any distance required, so as to secure any desired width of space between 115 the letters.

The knob of the letter-key L is made to screw on the top of the tube i^2 . Inside of this tube the spiral spring o^2 is placed, filling the cavity of the tube, and into the lower end of the tube is inserted the shaft u^2 , having next to its upper end a slot a^2 in the shaft long enough to permit the tube to slide down over the shaft far enough to depress the key-board the distance required. The spiral spring o^2 120 is of sufficient strength to sustain the pressure needed to force down the lever m the required distance without material compression of the spring, so that in using the letter-key the lever m , when thus forced down, reaches its 125 destination at or before the moment the lower end of the tube comes in contact with the key-board. When this contact with the key-board occurs, the shaft u^2 , under continued

pressure, remains stationary, and the tube by increased pressure slides down over the shaft, forcing down the key-board far enough to operate the hammer-lever C and to carry forward the carriage Q the distance required for the space between letters. The space between words is made by depressing the key-board only as often as required before beginning to print the next word. In operating the key-board for spacing between words the pressure may be applied at any convenient place on top of the key-board; but the use of the fixed knob c² for that purpose is preferred. If an increased width of space between letters is desired, it may be made by depressing the key-board in the same way that the space between words is made.

The use of the spiral spring in the construction of the letter-key, as above described, is preferred; but a straight spring v² is also used, one end of which is united to the lower end of the shaft u² by a flexible joint and the other end fixed solid on the upper edge of the lever m, the straight spring being of sufficient strength to operate the lever m and key-board K in succession in the same manner and on the same principle as they are operated by the letter-key in which the spiral spring is used; but when the straight spring is used the upper end of the shaft u² contains no slot, but is bolted fast in the lower end of the tube i², so as to prevent the tube from sliding upon the shaft and utilize the tube for depressing the key-board to the same extent as when used for that purpose in connection with the spiral spring.

Spacing between words without soiling the paper or other material on which the printing is done is accomplished as follows: That arm of the letter-wheel immediately beneath the hammer when the letter-keys are not in use is made short enough for the hammer-arm when descending to miss it, and thus leave the paper or other material to be printed on blank at that point, and such blank-points are repeated as often as the key-board is depressed, except when such depression is made by depressing the letter-keys. In this way the spaces between words or letters may be made of any desired length.

To prevent the key-board K when in operation from ascending or descending too far, a stop is provided, consisting of the clamp r², which is secured to the machine by a screw or other proper fastening, so that one arm of the clamp projects over the upper edge of the key-board and holds it down to its proper place, and the other arm projects under the key-board at sufficient distance beneath it to permit sufficient sweep of the key-board to operate the hammer-arm C, the ratchet I, and the carriage Q, and make the spacing between letters and words as above described, and in the lower arm of the clamp r² is placed the

set-screw s², with which the sweep of the key-board is regulated with the greatest precision.

I do not claim the combination, in a type-writing machine, of gear-arms, a type-wheel shaft, and a pinion carried by said shaft, said arms being brought independently in gear with said pinion to rotate said type-wheel in either direction from a fixed point and subsequently to return said type-wheel to its initial point.

What I claim, and desire to secure by Letters Patent, is—

1. The combination of the key-board K, the lever F, the carriage Q, the shaft J, carrying the wheels x and y, and the ratchet I, carried by the lever F and adjustable in the slot b, whereby the carriage is moved varying distances corresponding to the distances the ratchet may be set from the fulcrum of the lever, substantially as described, for the purposes specified.

2. The combination of the carriage Q, the shaft J, bearing the fixed wheels x and y, the hammer-lever C, and the lever F, carrying the ratchet I and united to the key-board and hammer-lever by suitable links, as E and H, all substantially as described, the arrangement being such that by elevation and depression of the key-board the stroke of the hammer-lever and forward movement of the carriage occur alternately, in the manner and for the purposes set forth.

3. The combination, in a type-writer, of the fixed wheel w, the ratchet T, the transverse bar v, the levers m, and the type-wheel A, geared to the shaft a, substantially as shown, for the purposes specified.

4. The combination, in a type-writer, of the type-wheel A, the shaft a, carrying the fixed wheels O and w, the ratchet T, the transverse bars r, s, z, and v, the springs k, the levers m, and the keys L, all substantially as described, for the purposes specified.

5. The combination, with suitable supports, of the transverse bars r, s, and z, carrying set-screws, the levers m, and the letter-key L, the arrangement being such as to limit the oscillation of the levers and arrest the rotary movement of the type-wheel when the desired character is brought into position, substantially as set forth.

6. The combination, in a letter-key for a type-writer, of the tube i², the spring o², and the shaft u², provided with a suitable slot, as a², engaging with a pin through the tube and slot and limiting the sliding movement of the tube over the shaft, with the key-board K, the levers m, and springs k, all substantially as described, for the purposes specified.

JOHN H. FORREST.
